UNITED STATES PATENT OFFICE

LELAND W. PIERCE, OF STOCKTON, ILLINOIS

LUBRICANT DISPENSING APPARATUS

Application filed August 19, 1929. Serial No. 386,966.

This invention relates to new and useful improvements in dispensing, and more particularly to a novel lubricant dispenser for dispensing oil for automobile engines.

5 The principal object of this invention is to provide an apparatus for dispensing cylinder oil without utilizing bottles or jars such as have heretofore been employed for transporting the oil from the pump to the 10 engine.

During the course of the following specification and claim, other important objects and advantages of the invention will readily become apparent.

15 In the drawings:

Figure 1 represents a front elevation of the novel apparatus showing in section the disposition of the pipe communicating the storage tank with the visible oil containing 20 receptacle.

Figure 2 represents a longitudinal sectional view through the oil reservoirs and through the adjacent soil.

Figure 3 represents an end elevation of 25 the oil displaying stand.

Figure 4 is an enlarged fragmentary vertical sectional view through the oil displaying container and associated structure.

Figure 5 represents a diagrammatic view 30 of the storage tank and the dispensing container.

Figure 6 is a horizontal sectional view taken substantially on line 6—6 of Figure 1.

Referring to the drawings, wherein like 35 numerals designate like parts, it will be seen that this invention includes an upwardly tapering hollow pedestal 5 of ovate cross section. Mounted upon this pedestal 5 is a base 6 upon which the row of dispensing receptacles 7 are mounted, the lower ends thereof being seated in recesses in said base and upon packing members 9. A dome 16 is provided for each receptacle, and this dome is provided with a circumferentially 40 extending flange 17. The dome 16 is securely maintained upon the upper end of the receptacle 7 by means of tie rods 18 the same being disposed through openings in the said flange 17 and having their threaded ends 45 anchored in the base 6.

An auxiliary receptacle in the nature of an overflow pipe 19 is provided within each receptacle. The lower end portion of the overflow pipe is provided with a pin opening for receiving the tapered end of the 55 needle valve 20, which is disposed through the threaded bushing 21. A foraminous guard 22 encompasses the receptacles 7 while a frame 23 extends upwardly and horizontally across the receptacle for supporting 60 electric lamps 24. The base 6 is constructed for each receptacle to provide a tapering bore 25 from which branches a smaller tapering bore 26. The dispensing hose 27 communicates with the bore 26 as at 28. Each dispensing hose 27 is provided with a nozzle 29 at its free end. It will be observed, that when the chamber 7 is filled to a predetermined level, that is, level with the upper end of the overflow pipe 19, should any of the 70 liquid overflow into the said pipe 19, the same will be retained therein until after the content of the chamber 7 has been depleted, whereupon the valve 20 may be opened to permit the liquid in the pipe 19 to escape into 75 the chamber 7.

In Figure 2 an elongated tank 30 is shown, and by means of a plurality of spaced partition walls 31, this tank is divided into a plurality of individual compartments for containing various grades of oil. In Figure 5 the tank 30 is also shown and a compressed air supply pipe 32 extends to the tank and longitudinally along the same. (Also see Figure 2). The portion of the pipe 32 extending across the tank 30 is provided with couplings 33 at predetermined spaced intervals. A plurality of filler pipes 34 extend downwardly from the surface of the ground, each to communicate with a compartment of the tank 30 and also with the air supply line 32 and one of the couplings 33. A cap 35 is provided for each filler pipe 34. A pressure gauge 36 is provided in the pipe line 32, while another gauge 37 communicates with the compartment 38 of the tank, these gauges being located within a pocket 39 in the earth. A pipe 40 extends from each of the oil containing compartments to communicate with the corresponding receptacle 7.

115

Each of the pipes 40 has a flow control valve 41 and a lever 42 for actuating the valve 41 and protrudes through the wall of the pedestal 5 in the manner as shown in Figures 1 and 3.

A pipe 43 extends from the air compartment 38 and leads in through a valve 44 to each receptacle 7.

It will thus be seen that the oil is discharged

- 10 through the pipes 34 into the proper compartments of the tank 30. The pipes 34 are then closed by the caps 35 and the air turned on in the line 32, this charging the compartment 38 and compress the oil in the remaining compartments, so that when the valves 42 are opened, the same will flow under pressure to corresponding receptacles 7. When the receptacles 7 (or the predetermined receptacle) are filled, the proper valves 41 are
- 15 closed and the valve in the airline is opened, so that the oil is discharged from the container to the receptacle through the hose 27 under pressure.

The compartment 38 is to have less pressure than the compartment 30 so as to act as an air cushion when filling the receptacle 7. This permits oil to flow into receptacle 7 when valve 42 is opened against the pressure in chamber 38. When the oil flowing from

- 20 chamber 30 is shut off, the oil runs out of compartment 7 due to the sub-pressure in compartment 38 without necessitating the admission of additional air.

While the foregoing description is in detailed language, it is to be understood that numerous changes in the specific shape, size and materials may be resorted to without departing from the spirit and scope of the invention as claimed hereinafter.

40 Having thus described the invention, what is claimed as new is:

In an oil dispensing device, a measuring container, means for delivering oil to the measuring container, means for draining oil from the container for use, a vertically disposed stationary excess oil receiving pipe in said container arranged in close proximity to one side wall thereof, said excess oil receiving pipe terminating short of the upper end of the container and above a point in the container indicating a measured quantity of liquid, the lower portion of the pipe having communication with the container, a valve mounted within the lower portion of said pipe for controlling the flow of oil from said pipe into said container, and means for operating the valve exteriorly of the measuring container and at a point adjacent to the lower end thereof.

60 In testimony whereof I affix my signature.
LELAND W. PIERCE.
